Primary Examiner — Karen E Kearney*Assistant Examiner* — Katherine Holbrow(74) *Attorney, Agent, or Firm* — Young & Thompson(57) **CLAIM**

The ornamental design for a display screen with graphical user interface, as shown and described.

DESCRIPTION

The sole FIGURE is a front view of a display screen with graphical user interface.

The broken lines showing of the electronic device are included for the purpose of illustrating environmental structure and form no part of the claimed design.
